UNITED STATES PATENT OFFICE.

JAMES A. NORTON, OF ODEBOLT, IOWA, ASSIGNOR TO PETER E. NORDELL, TRUSTEE, OF KIRON, IOWA.

COMBINED ICE AND WATER BOAT.

No. 863,747.

Specification of Letters Patent.

Patented Aug. 20, 1907.

Application filed November 13, 1906. Serial No. 343,261.

To all whom it may concern:

Be it known that I, JAMES A. NORTON, a citizen of the United States, residing at Odebolt, in the county of Sac and State of Iowa, have invented new and useful 5 Improvements in Combined Ice and Water Boats, of which the following is a specification.

My invention relates to navigation and the object of the invention is the construction of a boat operated by any motive power and especially adapted for use upon 10 shallow streams and lakes. It is equally adapted for navigation upon ice, as the same means of propulsion are as applicable to ice as to water.

The invention consists of an ordinarily constructed flat bottomed boat mounted upon a series of floats or 15 hollow cylindrical tubes, pointed at the forward ends and secured together, and propelled by paddles or fans secured to endless chains which run on sprocket wheels extending from each side of the boat.

I have illustrated my invention in the accompanying 20 drawing in which

Figure 1 is a view of my invention in side elevation showing the general plan of construction with some of the details omitted. Fig. 2 is a plan view of my invention showing the connection of the engine with the 25 propelling means. Fig. 3 is a cross section of the floats showing also the means of securing them to the boat. Fig. 4 is an enlarged detail view of a sprocket wheel operating the paddle chains and a section of the chain, showing also the paddles attached to the chain and a 30 section of the track in which is guided the arms attached to the paddles. Fig. 5 is a cross sectional view taken on line $x-y$, Fig. 4, showing also the post to which the shaft of the sprocket wheel is secured and a guide arm for the support of the chain. Fig. 6 is a detail view of guide arm as secured to one of the posts in 35 the side of the boat and the tracks for guiding the chain. Fig. 7 is a detail of paddle and braces which hold the paddles rigid in the water, showing also the chains in cross section and the rollers attached to the links. Fig. 40 8 is a detail view in side elevation of ratchet bar and sprocket wheel used in adjusting the distance of the paddles from the water or ice. Fig. 9 is a detail view in front elevation of ratchet bar and sprocket wheel, showing also a section of the side of the boat to which 45 the bar is adjusted and a worm gear and crank for the operation of the bar.

In the drawing, A is the boat and B the engine for its operation.

C, C, are the floats upon which the boat is mounted 50 and are secured to the bottom of the boat by the braces, a, a, a. Underneath each float is secured a shoe b, to protect the float from injury and also for use upon the ice.

D, D, are sprocket wheels adapted to revolve upon

the rear shafts, c, c, which are idlers, or secured to 55 posts d. The wheels D are held upon the shafts by the pins d''. The front wheels D' are secured to the shafts c', which extend through the posts d' and are operated by the engine through the shafts e and e', the sprocket wheels e'' and e'' and the chains e''. The posts d and d' are 60 fitted in the sides of the boat, having tongues d' which fit corresponding grooves in the sides of the boat and thus provide a water tight joint. The sprocket wheels D and D', have double spokes as seen in Fig. 5, the ends of each spoke having shoulders on each side. Over the 65 ends of the spokes are adjusted the chains E, E, to the links of which are attached at intervals the paddles F, F. The chains are in pairs or double, one pair on each side of the boat, the chains in each pair being connected at the joints of the links by the rods f, which serve 70 also as axes for the paddles. The paddles are held rigid in a vertical position when in the water by means of the braces f', f', which are secured to the links in front of the paddles. At each end of the rods f connecting the links of the chains carrying the paddles, are rollers G, G, 75 which are conveyed in tracks g, g, secured to the posts d, d', and h, at the sides of the boat and also to the guide arms i, i. The tracks are supported in a position eccentric to that of the chains. The guide arms are secured to the posts h, h, above the chains and extend 80 over the chains and down the side of the boat, inclosing the chains and supporting the tracks in which the chains are conveyed. As the paddles pass out of the water they are made to fold forward against the chain and thus offer less resistance to the air. An arm j is 85 pivotally secured at one end to a lug j' on each paddle. At the opposite end it bears a roller k, which is conveyed in a track l, secured to the posts d, d' and h, and follows the general course of the chain. On the lower side of the chains the track l is below the chains and 90 permits the paddles to maintain a vertical position, but on the upper course it passes below the chains, and thus the rollers k, following the course of the track, draw the paddles down, as seen in Fig. 4. Means are also provided for adjusting the paddles to correspond 95 to the depth of the water by raising or lowering the sprocket wheels bearing the chains.

Secured to the inside of the posts d and d' are the posts m, m, to which are secured the toothed bars n, n. Near each bar a brace o is secured to the inside of the 100 boat supporting a ring or collar p, which encircles a shaft r. The shaft supports at one end a toothed wheel s, adapted to mesh with the toothed bar, and at the other end a worm wheel t, both wheels being secured to the shaft. Secured to the collar and extending upward therefrom is a forked brace u, which incloses a worm wheel v which turns upon an axis in the forks and meshes with the worm t. A crank w is secured to

the axis of the worm v , and by the operation of the crank communicated through the worms and the toothed wheel and bar, the posts d and d' are raised or lowered and the position of the paddles with reference 5 to the water or ice regulated.

The boat is steered in the usual manner when in the water by means of the rudder H . When used upon the ice a grip or shoe may be added to the bottom of the rudder for gripping the ice.

10 Having described my invention, what I claim as new and desire to secure by Letters Patent, is—

1. The combination with a flat-bottomed boat, a series of floats or hollow tubes secured together upon which the boat is mounted, shoes secured underneath to said floats 15 for the protection of the floats, of endless chains run by sprocket wheels on each side of the boat, an engine for the operation of said sprocket wheels, paddles for the propulsion of the boat pivotally secured to said chains,

means for holding said paddles vertically rigid when in the water and means for raising and lowering the 20 sprocket wheels and adjusting the paddles with reference to the water, substantially as described.

2. The combination with a boat, a series of floats or hollow tubes upon which the boat is mounted, of sprocket 25 wheels on each side of the boat, means for the operation of said sprocket wheels, endless chains mounted upon said sprocket wheels, paddles for the propulsion of the boat pivotally secured to said chains, an arm pivotally secured to each of said paddles, tracks eccentric to the chains in which the arms are guided for folding the paddles as they 30 pass out of the water, and means for raising and lowering the sprocket wheels and adjusting the paddles with reference to the water, substantially as described.

In testimony whereof I have signed my name to this specification in the presence of two subscribing witnesses. 35

JAMES A. NORTON.
